DESIGN FOR A TOY DOG

Martin Berger, New York, N. Y., assignor to Metro Toy Company, New York, N. Y., a partnership

Application October 11, 1945, Serial No. 122,744

Term of patent 7 years

(Cl. D34—2)

To all whom it may concern:

Be it known that I, Martin Berger, a citizen of the United States of America, and resident of New York, county and State of New York, have invented a new, original, and ornamental Design for a Toy Dog, of which the following is a specification, reference being had to the accompanying drawing, forming a part thereof, in which

Fig. 1 is a side view of a toy dog embodying my new design.

Fig. 2 is a top view of the toy dog shown in Fig 1, and

Fig. 3 is a front view of the toy dog.

I claim:

The ornamental design for a toy dog, as shown.
MARTIN BERGER.
